FRANZ DOERSCHUCK, OF NEW HAVEN, CONNECTICUT.

Design No. 3,291, dated December 15, 1868.

DESIGN FOR A CABINET-ORGAN CASE.

The Schedule referred to in these Letters Patent and making part of the same.

To all whom it may concern:

Be it known that I, FRANZ DOERSCHUCK, of New Haven, county of New Haven, and State of Connecticut, have invented a new and original Design for Cabinet-Organ Cases; and I do hereby declare the following to be a full, clear, and exact description of the same, reference being had to the accompanying drawings, and to the letters of reference marked thereon.

Said drawings constitute a part of this specification, and represent, in—

My invention relates to a new and original design in the form of a case for cabinet-organs, and consists in forming the said case of suitable material, having the corners rounded, as shown in fig. 2. The object of this is to give a more finished appearance to the case, and save the expense attending the use of panel-work and mouldings.

The sides of the case may be slightly curved from a straight line, as shown in fig. 2, but the principal idea of my invention is, that wherever, in the cases now made, a square corner is used, in my case a graceful curve or oval takes its place.

My case is intended to be made in forms of the required shape and size to make one-half of the said case, with the rounded corners and slightly-curved sides, at one operation, and so, with two sets of forms, a whole case is made. The ends of the two opposite halves of the said case are then glued together, thus forming a continuous case, as shown in figs. 1 and 2.

Having thus fully described my invention,
What I claim, is—

The design for cabinet-organ cases, as herein described.
